UNITED STATES PATENT OFFICE.

JAMES H. MANN, JR., OF LITTLE ROCK, ARKANSAS, ASSIGNOR TO TRANSIT VENDING MACHINE COMPANY, OF PINE BLUFF, ARKANSAS, A CORPORATION OF ARKANSAS.

VENDING-MACHINE.

1,341,921.

Specification of Letters Patent. Patented June 1, 1920.

Application filed March 9, 1918. Serial No. 221,509.

To all whom it may concern:

Be it known that I, JAMES H. MANN, Jr., citizen of the United States, residing at Little Rock, in the county of Pulaski and State of Arkansas, have invented certain new and useful Improvements in Vending-Machines, of which the following is a specification, reference being had to the accompanying drawings.

10 This invention relates to vending machines and more particularly to a machine of that general character shown and described in Patent No. 1,217,616, issued to me February 27, 1917.

15 It is the primary purpose and object of the present invention to provide improved means for mounting and arranging the coin controlled delivery mechanism within the machine case in such manner that it may be 20 bodily removed therefrom when it is necessary to replace or repair any of the parts.

It is also another important object of the invention to provide a magazine case for the commodity to be vended and means for 25 removably retaining said magazine case within the outer case or body of the machine, said magazine case being formed with means whereby the coin controlled mechanism and the coin guide or chute may be 30 compactly assembled and operatively mounted upon the back or rear wall of said case.

It is also one of the secondary objects of the invention to provide a magazine case, coin chute and the main operating parts of 35 the mechanism which can be readily stamped or cut out of sheet metal plates by means of suitable dies whereby the manufacturing cost of such machines may be appreciably reduced.

40 It is a further general object of my invention to improve the original vending machine above referred to in the several particulars stated to the end that the utility and serviceability of such machines may be 45 enhanced and the machine as a whole rendered commercially more desirable.

With the above and other objects in view, the invention consists in the improved combination, construction and arrangement of 50 the several parts as will be hereinafter more fully described, subsequently claimed and illustrated in the accompanying drawings in which similar reference characters design-

nate corresponding parts throughout the several views and wherein:—

55 Figure 1 is a front elevation of a vending machine embodying the present improvements.

Fig. 2 is a similar view, the face plate of the machine case and the cover plate for 60 the mechanism being removed.

Fig. 3 is a vertical sectional view taken on the line 3—3 of Fig. 2.

Fig. 4 is a horizontal section taken on the line 4—4 of Fig. 1.

65 Fig. 5 is a section taken on the line 5—5 of Fig. 2.

Fig. 6 is a rear elevation of the magazine case removed.

70 Fig. 7 is a detail vertical section taken on the line 7—7 of Fig. 6.

Fig. 8 is a fragmentary horizontal section taken on the line 8—8 of Fig. 6.

75 Fig. 9 is a fragmentary side elevation of the magazine case.

Referring in detail to the drawings, 5 designates the rear wall and 6 the opposite side walls of the bottomless outer case body of the machine. The rear wall 5 is centrally provided at its upper and lower ends 80 with apertures 7 for the purpose of receiving suitable attaching screws, the metal surrounding said apertures being outwardly punched or projected. This rear wall of the case body is further provided at each side 85 of the apertures 7 with outwardly struck protuberances 8.

The particular purpose of these indentations will be hereinafter fully explained.

The side walls 6 of the case body are provided upon their longitudinal edges with narrow laterally projecting flanges 9, each of the side walls adjacent to its lower end being cut away or recessed at its forward edge to provide the relatively narrow downwardly projecting portions, each of which likewise terminates in an outwardly projecting flange 9'.

10 designates the removable face plate for the machine case, the longitudinal edges of 100 which are inwardly turned to provide channels for the reception of the flanges 9 on the side walls of the case body. It will be noted that the lower end of the face plate 10 is outwardly curved or bulged and the 105 flanges 9 on the side walls of the case are

recessed or cut away at the correspondingly curved portions of said side walls. This plate has spaced longitudinally extending slots 11 cut therein through which the contents of the magazine may be viewed and is also provided below the slots 11 with a relatively short horizontal slot 12. The surface of this plate may be suitably ornamented and contains the necessary directions for the proper operation of the machine.

The magazine case for the machine also includes a rear wall 13 and the longitudinally extending side walls 14. This magazine case is of slightly less width than the outer body case of the machine and is adapted to be fitted within the latter. The rear wall 13 at its upper end is centrally provided with the screw receiving opening 15, the edge of which is outwardly projected to seat upon the edge of the opening 7 in the rear wall 5 of the case body. The wall 13 of the magazine case is further provided at its upper and lower ends with the outwardly punched protuberances 16. These protuberances contact with the rear wall of the outer case, and space the walls of the magazine case therefrom so that the walls will not adhere by the formation of rust and render it difficult to remove the magazine case. The protuberances 8 on the outer case wall space the major portion of said wall from the part upon which the machine is mounted to obviate undue marring of the finished surface.

The lower ends of the side walls 14 of the magazine case are reduced in width as indicated at 17 and the upper end of a plate 18 is fitted between the side walls 14 immediately above the reduced portion 17 thereof and is engaged at its opposite edges upon said reduced portion. This plate to all appearances constitutes a continuation of the removable front plate 10 of the case body. The plate 18 at its upper end is provided with portions at the vertical edges thereof for engagement in slots or recesses in the side walls 14 of the magazine case as indicated at 18', and the vertical edges of said plate at its lower end are recessed to receive forwardly projecting lugs 19 on the relatively narrow lower end portions 17 of the case walls. In this manner the plate 18 is securely locked in position. At the lower end of the plate 18 a forwardly projecting article receiving tray or pan 20 is formed. The upstanding flange 21 at the forward edge of this pan has its ends turned inwardly to provide channels or grooves for the reception of the flanges 9' on the lower ends of the side walls 6 of the case body. The magazine case above described as well as the outer body or case of the machine is stamped from a sheet metal plate, and the coin controlled mechanism, as well as the article delivery mechanism is wholly carried by and mounted within the magazine case

and is bodily removable therewith from the outer case of the machine. As in the original patented construction above referred to I provide an article delivery plate or shelf 22 having angular ears 23 at its opposite ends loosely mounted for rocking movement upon a rod 24, the ends of which are engaged in openings in the side walls 14 of the magazine case. This delivery plate is normally held in a horizontal position by means of the spring 24' engaged upon the rod 24. One of the ears 23 is formed with teeth as shown at 25 which engage with the teeth 27 formed in a metal bar 26 which is slidably mounted upon the rear wall 13 of the magazine case between the guide tongues or flanges 27' struck from the rear wall 13 and one of the side walls 14 of the case. This rack bar has its lower end portion formed into a suitable handle 28, which extends downwardly below the lower end of the case body. In one edge of the bar 26 adjacent to the lower end thereof the shoulder 29 is formed, and below said shoulder the edge of the bar is obliquely inclined as at 30. 31 designates the locking bar or lever which is fulcrumed upon the wall 13 of the case as indicated at 32 and is movable under a guide tongue 33 struck from said wall. A spring 34 normally holds said lever in operative engagement with the edge of the rack bar. This spring is likewise connected to a second lever 35 fulcrumed upon the wall 13 of the case as at 36. In addition, a relatively heavy coil spring 37 is connected at one of its ends to the lever 35 and at its other end to a lug 38 struck from the case wall 13. One end of the lever 35 is engaged between an off-set portion 39 in the upper end of the rack bar 26 and the rear wall of the case. The rack bar at its upper end is toothed as at 40 for engagement with the spring held detent 41 mounted on the case wall whereby the rack bar is held in intermediate position and its return to normal position prevented before the completion of its operating movement. The rack bar 26 is further provided with a lug 42 struck therefrom which is adapted to engage an upstanding lug 43 on the rear edge of the plate 22, said lug acting as a stop to limit the downward movement of the rack bar.

The coin chute 44 is stamped or pressed from a sheet metal plate, said chute having a relatively wide upper portion extending substantially the entire width of the magazine case, said wider portion of the sheet metal plate having downwardly and inwardly inclined flanges 45 leading from the coin slots 46 which are formed in the opposite side walls 14 of the case and directing the coins into the relatively narrow vertical portion of the coin chute. The slots 46 of course coincide with similar coin slots in the side walls 6 at the opposite ends of the ma- 130

chine case. The narrow portion of the coin chute is likewise provided on its longitudinal edges with narrow angular flanges 47. These flanges as well as the flanges 45 are 5 formed with lugs or projections to extend through openings 48 formed at the requisite points in the rear wall 13 of the case. With a suitable tool, these lugs at their opposite ends are laterally swaged or bent and 10 locked to the case wall. In this manner, the coin chute is held absolutely rigid against any possibility of movement upon the wall of the magazine case. The flange 47 on one edge of the chute is provided with recesses 15 or openings therein at the proper points for the accommodation of the pivoted levers 31 and 35 respectively.

The coin controlled article delivery mechanism as above described, operates in a manner quite similar to the mechanism disclosed 20 in my prior patent. Thus when a coin of the proper denomination is deposited, it moves downwardly by gravity between the rear wall 13 of the magazine case and the 25 front wall of the coin chute and finally lodges between the edge of the lever 31 extending within the chute and the opposite side flange 47 on the wall of the coin chute. The lever is thereby held against movement 30 and when the rack bar 26 is forced upwardly, the shoulder 29 on the edge of said bar will not contact with the lower end of the lever 31. Thus the teeth of the rack bar coacting with the teeth 25 will rock or oscillate the plate 22 whereby the lowermost 35 package of gum or other commodity in the magazine is delivered and falls downwardly by gravity into the tray 20 on the lower end of the plate 17. In this operating movement of the rack bar, the end of the lever 35 is projected across the coin chute so that another coin if deposited cannot drop downwardly in the chute and prevent the return movement of the lever 31 and the rack bar 40 45 to their normal positions.

All of the operating parts above referred to as well as the coin chute, of course excepting the springs, are stamped from sheet metal. It will be noted that they are very 50 compactly arranged upon the rear wall of the magazine case so that there will be ample room for the gum or other commodity, and yet the magazine case is of minimum depth.

55 The operating mechanism is covered by means of a sheet metal plate 49 flanged at its opposite longitudinal edges as shown at 50. These flanges adjacent their upper and lower ends are notched or recessed as indicated at 51. Lugs 52 are struck inwardly from the side walls 14 of the magazine case 60 at their upper ends, said lugs being disposed in a plane in spaced parallel relation to the wall of the coin chute. Additional spaced lugs 53 are also struck inwardly from each

side wall 14 in spaced relation to its lower end, the latter lugs being disposed out of alignment with each other longitudinally of the wall. Between the lugs 52 and 53, longitudinally extending flanges 54 are struck 70 inwardly from the side wall 14 of the case. In inserting the plate 49, the notches 51 in the off-set flanges 50 are disposed in registering relation with the lugs 52 and the uppermost lugs 53 on the side walls of the case, 75 said flanges resting upon the flanges 54. The plate 49 is then forced downwardly so that the upper ends of the flanges 50 above the notches 51 will be engaged under the lugs 52 and also under the upper lugs 53 on 80 the side walls of the case. The flanges 50 at the lower end of the plate 49 ride over and have frictional engagement upon the lower inwardly projecting lugs 53. This downward movement of the plate 49 is limited by 85 the stop shoulders 55 formed upon the flanges 50 at their upper ends and which are adapted to coact with the lugs 52. The plate 49 at its lower end bears the word "Empty" and when the last article or package has 90 been delivered from the machine, this word will be clearly visible through the slot or opening 12 in the face plate of the machine case. The plate 49 entirely covers the coin 95 chute and operating mechanism above the delivery plate 22 so that the packages of gum or other commodity within the magazine cannot by any possibility contact with the parts of the mechanism and derange the same or prevent their proper operation.

Between the reduced lower ends of the side walls of the magazine case and rearwardly of the plate 18, the coin cup indicated at 56 is adapted to be inserted. Exterioly of the magazine case and upon one side wall 105 14 thereof, a locking lever 57 is arranged whereby the coin cup is locked against removal. The particular mounting and construction of this locking lever and of the coin cup is fully shown and described in 110 my prior patent, No. 1,278,186, issued September 10, 1918, and *per se* constitutes no part of the present invention. It will not, therefore, be herein fully described in detail. It will suffice to state that the coin cup locking lever is mounted upon the magazine case wall so that this lever also is removable with the operating mechanism from the exterior of the body or case of the machine.

To the upper end of the rear wall 5 of the outer case body a lid or cover 58 is hinged and, as fully disclosed in my pending application carries a suitable lock 59 the bolt of which coacts with the coin cup 125 locking lever whereby said lid or cover is locked in its closed position.

After the magazine case has been arranged within the outer case body of the machine and the magazine charged with the 130

commodity, a plate of glass or other transparent material shown at 60 is engaged at its longitudinal edges upon the edges of the side walls 14 of the magazine case and rests 5 at its lower end upon the shoulders 61 formed on said walls. It is of course understood that the rear wall of the case body has been secured to a wall, standard, or other support at its lower end by means of 10 a fastening screw, and when the magazine case is arranged within the outer case, the opening 15 at the upper end of its rear wall registers with the opening 7 at the upper end of the case wall 6 and a second 15 screw is inserted to securely fasten the outer case at its upper end to the wall and to effectually prevent the removal of the magazine case. The lower fastening screw is entirely covered and hidden by the lower end 20 of the magazine case, and of course it is quite impossible for one to obtain access to either of the fastening screws whereby the machine may be bodily removed from its applied position. After the glass plate 25 60 has been arranged in place, the cover plate 10 is finally forced downwardly upon the flanges 9. The lid or cover is then closed, and the flange 62 on the free edge thereof engaging over the upper end of the 30 cover plate 10 prevents the upward sliding movement of the latter plate.

If desired, the lid or cover 58 may be provided upon its under side with a coin directing member 63 one end of which is disposed 35 contiguous to a coin slot 64 in the flange 62 on the cover. The upper end of the plate 49 and of the wall of the coin chute are recessed or cut away so that the coin when inserted through the slot 64 may gravitate 40 rearwardly and downwardly into the space between the wall of the chute and the rear wall 13 of the magazine case. However, this front entrance slot for the coin and the coin directing member 63 may, if preferred, 45 be dispensed with and coin slots provided only in the opposite sides of the case at its upper end.

From the foregoing description taken in connection with the accompanying drawings it is believed that the construction, 50 manner of assemblage and operation of the several parts and the numerous advantages incident thereto will be fully and clearly understood. The machine as herein described is primarily designed for use in railroad coaches, where it is mounted between adjacent windows: upon the backs of theater chairs, and in like instances where the available space for mounting the machine is comparatively limited. It is also an important factor in the adaptation of vending machines to such uses, that it shall be possible to recharge the machine and remove the coins in a very expeditious manner, so that all of the machines in a rail-

way coach or in a theater may be attended to with the expenditure of a minimum of time. It is also a requisite to the practical commercial success of such machines that they shall be so constructed that they are 70 not liable to be damaged or put out of order by curious individuals attempting to operate the machine in order to discover the secret of its operation.

Finally, it is of primary importance that 75 the machine shall be so constructed that access may be readily had to the various parts of the operating mechanism for the purpose of renewing or repairing the same, without necessitating the removal of a large 80 number of screws or other fastening elements, or the bodily dismounting of the machine from its support.

The several desirable features above referred to are all attained by means of the 85 present invention. The operating mechanism whereby the articles are vended, is very compactly arranged, all of the elements being disposed substantially in the same plane so that as a whole this mechanism occupies but little space at the rear of the magazine. When it is necessary to obtain access to the mechanism, the very simple operation of opening the case cover or lid and removing the cover plate 10 and the 90 upper fastening screw and then pulling downwardly and forwardly upon the article receiving tray, will result in the bodily removal of the magazine and all of the operating mechanism from the outer case or 100 body of the machine. The plate 49 can then be readily removed and the mechanism exposed. The magazine and operating mechanism can be as readily positioned within the outer case and again secured by means 105 of the single fastening screw, after which the cover plate 10 is replaced. The magazine case being stamped from a single metal sheet can be very inexpensively manufactured, and the manner of fastening the coin 110 chute and operating elements upon the rear wall of this case, avoids the necessity of employing numerous fastening screws which are liable to become loosened and permit the relative movement of the parts. As the operating parts and the case body are likewise stamped from sheet metal it will be appreciated that the machine in its entirety can be produced at relatively small cost while at the same time, in view of the simple and 115 compact construction, great durability is obtained and even though the machine be subjected to great jar or vibration, the parts of the operating mechanism will not be liable to relative displacement. The machine is 120 also very light in weight, and a large number of machines may be carried by a single workman and erected or mounted in place in railway cars or coaches.

While I have herein shown and described 130

the preferred form of construction and relative arrangement of the various parts, it is to be understood that the machine is susceptible of considerable modification there-
5 in and I, therefore, reserve the privilege of adopting all such legitimate changes as may be fairly embodied within the spirit and scope of the invention as claimed.

Having thus described my invention,
10 what I claim is:—

1. In a vending machine, a magazine case stamped from a single metal sheet and having a rear wall and parallel side walls, article delivery mechanism mounted upon said 15 rear wall, said wall having guide tongues struck therefrom to retain various parts of the delivery mechanism in close contact with said wall and in their proper relative operative positions, each of the side walls of the 20 case being provided with inwardly struck guide tongues and flanges, and a cover plate for said mechanism longitudinally movable downwardly between the side walls of the case and coacting at its edges with said 25 tongue and flanges whereby the cover plate is frictionally held in its applied position.

2. In a vending machine, a magazine case stamped from a single metal sheet and having a rear wall and parallel side walls, article delivery mechanism operatively mounted upon said rear wall, each of the 30 side walls having flanges struck inwardly therefrom, and a removable cover plate separating the delivery mechanism from the 35 article receiving chamber and having longitudinal flanges recessed to receive the flanges on said side walls, said plate being adapted for longitudinal movement to move the recesses out of registering relation with 40 said flanges and cause the flanges to frictionally coact with the edges of the cover plate and thereby retain the latter in place.

3. In a vending machine, a magazine case stamped from a single metal sheet and hav-
45 ing a rear wall and spaced parallel side

walls, coin controlled article delivery mechanism mounted upon the rear wall of said case, a coin directing chute extending vertically of said rear wall, said wall being provided with spaced openings therein and the 50 coin chute having lugs locked in said openings to retain the coin chute in its applied position upon the case wall, a removable plate extending over the delivery mechanism and the coin chute and separating the same 55 from the article receiving chamber of the case and means on the opposite side walls of the case to coact with the edges of said plate and frictionally retain the same in its applied position.

4. In a vending machine including an article delivery mechanism, the combination with an inner magazine case provided with means for detachably carrying said mechanism, the magazine casing having means on 60 its rear wall to retain various parts of said mechanism in close contact with said rear wall, of a cover plate fitting within said magazine case, means carried by the sides of said magazine case overlying the longitudinal edges of said cover plate for detachably supporting said plate for housing and protecting said mechanism and its associated elements, an outer casing conforming to and adapted to removably receive said magazine 65 case with its back and sides in spaced relation thereto, whereby the mechanism and its associated elements and the magazine case may be removed as one body, and interengaging means carried by the adjacent 70 backs of both casings for spacedly and rigidly connecting said casings in detachable relations.

In testimony whereof I hereunto affix my signature in the presence of two witnesses. 75
